LUBRICATING APPARATUS FOR JOURNAL BOXES

Charles B. Royal, Chicago, Ill.

Application December 18, 1931
Serial No. 581,949

5 Claims. (Cl. 308—88)

This invention relates to lubricating apparatus for journal boxes and more particularly to journal boxes used on railway cars, locomotives, etc. The invention constitutes, to some extent, an improvement upon my application, Serial No. 513,042, for Lubricating apparatus for railway journal box.

An object of the invention is to provide lubricating apparatus which will supply a uniform and even flow of lubricant to a journal, and which may be readily removed and inserted within a railway journal box. A further object is to provide improved resilient means for maintaining a lubricant bearing material, such as felt, against a side wall of the journal. Another object is to provide sealing means for preventing the escape of lubricant along the journal wall and for preventing the ingress of dust, etc. into the interior of the journal box. Other objects and advantages will appear as the specification proceeds.

The invention is fully described in the following specification and shown in the accompanying drawings, in which:—

25 Figure 1 is an end sectional view of apparatus embodying my invention, the section being taken as indicated at line 1 of Fig. 3; Fig. 2, a transverse sectional view, the section being taken as indicated at line 2 of Fig. 1; Fig. 3, a vertical sectional view, the section being taken as indicated at line 3 of Fig. 1; Fig. 4, an enlarged detail sectional view of the sealing strip employed near the rear of the journal; Fig. 5, a front view of the lubricating apparatus; Fig. 6, a plan view 35 of the lubricating apparatus, removed from the journal box; Fig. 7, a broken sectional detail view of a spring hinge employed in the preferred form of my invention; and Fig. 8, a front, partly sectional view of a modified form of lubricating device constructed in accordance with my invention.

In the preferred form of lubricating apparatus, illustrated in Figs. 1 to 7, inclusive, A designates a journal box which may be of the usual or any suitable construction. The box is shown equipped with a hinged cover B. As shown more clearly in Figs. 1 and 2, the box A is provided at an intermediate point with integral lugs C which provide shoulders at C'.

50 Secured within the upper part of the journal box is a bearing D which may be of any suitable construction. As illustrated, a journal E engages the bearing D and is provided at its outer end with a collar E'.

55 My improved lubricating apparatus comprises

generally frame mechanism for supporting strips of lubricant bearing material, such as felt, yieldably against the side walls of the journal, means for spreading the frame to permit ready removal thereof from the journal box, means for limiting the swing of the lubricant bearing strips of felt, and also resilient means which prevent the escape of lubricant from the journal box.

In the illustration given in Figs. 1 to 7, inclusive, 10 designates strips or pads formed of felt or other suitable material. The felt pads are yieldably supported within frame 11. As shown more clearly in Figs. 5 and 6, the frame comprises a substantially U-shaped front member 12 and a similar rear U-shaped member 13. The front 70 and rear members 12 and 13 are connected by side rails 14. Short bracket spurs 15 are secured to the front and rear ends 12 and 13, and are preferably twisted or turned slightly. The bracket members 15 support one flange 16 of a hinge member 17. The upper flange 18 of the hinge is secured to a frame strip 19 which is secured to one of the felt pads 10. The hinge 17, which is of a well known construction, is provided with a spring 20 and the flanges 16 and 18 80 are so positioned as to contact when the pads 10 are swung to the inner position, shown more clearly in Fig. 5, thus definitely limiting the inward swing of the lubricating pads.

As shown more clearly in Figs. 1, 2, 5 and 6, 85 the forward ends of frame strips 19 are turned to form cam spurs 21, these cams being adapted to engage the inner side of the journal collar E' and to spread the inner frame members 19 and pads 10 as the lubricating apparatus is drawn 90 forwardly to remove it from the box. In order to permit full outward swing of the members 19 and cams 21, the front end member 12 is bent outwardly to form half loops 12a. As the members 19 and 21 swing outwardly, they enter the 95 loop portions 12a and enable the felt members 10 to be retracted sufficiently to clear the collar E' of the journal E.

One of the difficulties which has attended the use of lubricating apparatus of this type has been 100 the loss of lubricant along the rear side of the journal, the lubricant within the box being unconfined and free to flow within the box, is subjected to violent vibration and is thrown or splashed about the box and particularly along the rear side of the journal. The lubricant has had a tendency to flow along the rear portion of the journal wall and to escape under the portion of the axle adjacent the journal and journal box. I have found that this difficulty can be 110

overcome by providing a sealing strip or wall of felt or other suitable material and shaping it so as to embrace the bottoms and sides of the rear portion of the journal. As shown more clearly in Figs. 3, 4 and 5, the felt wall 22 is supported by the vertical flange 24 of an angle iron connection 25. The connection 25 is secured by suitable means to the rear end piece 13. Preferably, the rear wall 22 is cut away centrally along a circular line 26 to receive the journal E and thus forms a tight seal about the lower portion of the journal.

In addition to serving as a baffle or back stop to prevent the loss of lubricant, the felt wall 22 tightly seals the lower portion of the chamber against dust, etc. which normally enters the chamber at a point between the journal box and the adjacent axle portion.

In order to insure the apparatus against the jar and vibration to which it is subjected in the journal box, I prefer to extend the felt pads 10 so as to provide a cushioning portion 10a below the bottom of the metal frame. This extension may be from one-half to one inch long. Also, I prefer to provide baffle 22 with a similar extension 22a, which supports the rear part of the metal frame above the bottom of the journal box and also forms a seal against the bottom of the journal box.

Any suitable means may be employed to secure the felt wall 22 to the resilient support 23 and the felt walls 10 to the inner frame member 19. In the illustration given, split rivets 27 are employed.

In the operation of the device, the frame may be inserted within the journal box by spreading the spurs 21 and bending the resiliently supported rear wall 22. After the frame has cleared the collar E' of journal E, the spurs may be released, thus allowing the felt pads 10 to be drawn up against the sides of the journal. In this position, the tops of the side and end walls will abut shoulders C' of the journal box and will be held against rotary movement. The collar E' also cooperates with the rear wall of the box to prevent longitudinal movement of the lubricating device. Any other suitable means, however, may be employed for securing the lubricating apparatus within the box and below the journal.

It will be observed that the hinges 17, while they allow outward movement of the inner frame 19 and pads 10, definitely limit the swing of these members beyond the position shown more clearly in Fig. 5. This limiting of the swing of the members aids materially in inserting or removing the apparatus from the journal box.

In removing the apparatus from the journal box, the operator may grasp the lubricating frame with his hands or with tongs and exert a directly forward pull, thus bringing the spurs or spreaders 21 in contact with the inner wall of the collar E', and serving to spread the entire inner frame 19 and felt pads 10 so as to clear the collar E'. Half loops 12a of the end member 12 permit wide retraction of the spurs 21 and inner frame member 19. The rear felt wall 22 yields together with the resilient strap 23 and thus clears the collar E'.

In the modified form of apparatus illustrated

in Fig. 8, the felt pads 28 are supported by resilient spring strips 29 which are secured to the frame in the manner described in my application, Serial No. 513,042. In order to prevent the felt pads 28 from swinging inwardly to substantially collapsed position, I employ chains 30 which are secured to the frame 31 and to the top portion of spring strips 29. A sealing wall 32, substantially as described in connection with the preferred form of apparatus, is secured to the rear frame member 31.

The lubricating apparatus, both in its preferred and modified form, effects a tight sealing of the journal box against escape of lubricant and the inflow of dust; also, the apparatus may be readily inserted and withdrawn from the box in a very short time and with a minimum of effort.

The foregoing detailed description has been given for clearness of understanding only, and no unnecessary limitations should be understood therefrom, but the appended claims should be construed as broadly as permissible, in view of the prior art.

I claim:

1. A removable lubricating device for use in a journal box with a journal equipped with a collar, comprising a frame, lubricating pads carried by the frame and yieldably urged toward the journal, and cam spurs associated with said pads and adapted to engage the collar of said journal to spread said pads when the lubricating device is withdrawn.

2. A removable lubricating device for use in journal boxes comprising a frame, pad-carrying frames yieldably secured to said first-mentioned frame, spring means carried by said first-mentioned frame urging said pad-carrying frames toward the journal, pads carried by said pad-carrying frames, and cam spreader spurs connect- 116 ed to said pad-carrying frames.

3. A lubricating device for journal boxes comprising a frame having U-shaped front and rear ends and connecting rails, pad frames yieldably connected to said frame, pads carried by said pad frames, spring means urging said pad frames inwardly, and cam spurs connected to said pad frames, said front end of the frame being provided with a loop portion receiving said pad frames when said pad frames are swung rearwardly.

4. A lubricating device for journal boxes, comprising a frame, lubricant conveying pads carried by said frame and contacting with the journal, and a sealing pad carried by said frame and engaging the rear portion of said journal, said lubricant conveying pads and said sealing pad being provided with cushioning extensions which support the frame above the bottom of the journal box.

5. A lubricating device for journal boxes comprising a substantially rectangular frame adapted to fit within a journal box, pad supports secured to the sides of said frame and with their free ends inclined inwardly and adapted to swing below said journal, pads carried by said supports, and means for limiting the inward swing of said supports.

CHARLES B. ROYAL.
